UNITED STATES' PATENT OFFICE.

LEE S. HALDEMAN, OF MARIETTA, PENNSYLVANIA.

STOVE AND FURNACE GRATE.

1,147,502.

Specification of Letters Patent.

Patented July 20, 1915.

Application filed April 25, 1914. Serial No. 834,539.

To all whom it may concern:

Be it known that I, LEE S. HALDEMAN, a citizen of the United States, residing at Marietta, in the county of Lancaster and State 5 of Pennsylvania, have invented new and useful Improvements in Stove and Furnace Grates, of which the following is a specification.

The invention relates to stove or furnace 10 grates, and has for its primary object to provide a grate wherein the bed thereof is of novel form, including oval-shaped disks rotatably mounted within the grate frame so as to permit the shaking of the grate for 15 the dumping of the fuel or the shaking thereof.

Another object of the invention is the provision of a grate which is extremely simple in construction, reliable and efficient in its 20 operation, and inexpensive in manufacture.

With these and other objects in view, the invention consists in the construction, combination and arrangement of parts as will be hereinafter fully described, illustrated in 25 the accompanying drawing, and pointed out in the claim hereunto appended.

In the drawing: Figure 1 is a perspective view of the grate constructed in accordance with the invention. Fig. 2 is a vertical horizontal sectional view showing the oval-shaped disk in normal position. Fig. 3 is a similar view showing the grate in dumping position. Fig. 4 is a vertical longitudinal sectional view through the grate. Fig. 5 is 30 a perspective view of the handle or crank for shaking the grate. Fig. 6 is a fragmentary horizontal sectional view through the shaft and the handle crank connected thereto.

Similar reference characters indicate corresponding parts throughout the several views in the drawing.

Referring to the drawing in detail, A designates a stationary grate frame, which may be of any desirable shape, having spaced 45 transverse bars B, the said frame A being supported within the stove or furnace in any desirable manner. Bolted or otherwise secured centrally to the under side of the frame A at opposite ends thereof are bearing plates 5 which detachably secure a rotatable shaft 6 upon the same, the forward or front end of the shaft being formed with

a dove-tail shaped portion 7 with which engages a detachable crank or handle 8, the same being formed with a socket 9 correspondingly shaped to the portion 7 for receiving the same, and this crank or handle is designed to permit the shaking of the grate or the turning of the same for the dumping of the fuel from the fire box of the stove or 60 furnace.

Secured to or integral with the shaft 6 and arranged between the bars B of the frame A are oval-shaped disks 10 which serve as movable grate bars to coöperate 65 with the bars B of the frame A for supporting the fuel in the fire box. It will be noted that on rocking the disks 10 by slightly turning the shaft 6 in the reverse direction the fuel can be shaken, and on turning the 70 said shaft 6 a half circle the disks 10 will be turned to have their longer extent vertically disposed, and thereby permit the dumping of the fuel from the fire bed.

From the foregoing it is thought that the 75 construction and manner of operation of the device will be clearly understood, and therefore a more extended explanation has been omitted.

What is claimed is:

A stove or furnace grate comprising a frame having a series of spaced parallel transverse bars, a shaft journaled in the frame centrally thereof and having joined thereon a series of oval-shaped members 85 with their marginal edges made flat to provide cutting edges, the said oval shaped members being arranged between the bars, the said shaft being extended without the frame and having a dove-tail shaped portion 90 formed on the said extension, and a handle having a socket three walls of which interfit with the dove-tailed portion of the shaft, the socket being sufficiently large to permit of the detachable engagement of the 95 handle with the shaft for the revolving of the same.

In testimony whereof I affix my signature in presence of two witnesses.

LEE S. HALDEMAN.
